UNITED STATES PATENT OFFICE.

OTTO SOHNI, OF SCRANTON, PENNSYLVANIA.

DESIGN FOR A DIE OR CUTTER FOR PUNCHES.

SPECIFICATION forming part of Design No. 30,236, dated February 21, 1899.

Application filed January 26, 1899. Serial No. 703,516. Term of patent 7 years.

To all whom it may concern:

Be it known that I, OTTO SOHNI, a citizen of the United States, and a resident of Scranton, in the county of Lackawanna and State of Pennsylvania, have invented a certain new and original Design in Punch Dies or Cutters; and I do declare the following to be a full, clear, and exact description of the invention, such as will enable others skilled in the art to which it appertains to make and use the same, reference being had to the accompanying drawings, and to letters of reference marked thereon, which form a part of this specification.

Figure 1 of the drawings is a representation of a perspective view of the invention. Fig. 2 is a central vertical longitudinal section thereof. Fig. 3 is a section on line $x-x$, Fig. 2. Fig. 4 is a bottom plan view of the invention.

This invention has relation to a certain new and original design for a die or cutter for punches; and it consists in the novel form and configuration thereof herein shown and described.

The cutter is of oblong character and convex at its end portions, which are connected by intermediate side walls of reverse curvature. This convexo-concave superficies has an inner bevel or inclination from the flat top of the cutter and is caused to terminate in a

plane parallel with said top by intersection in a sharp cutting edge with a vertical inner wall carried upwardly some distance to the inner face of the body portion of the cutter. 35 This sharp edge forms the outer cutting edge of the device and is of double-loop form, contracted at its central portion.

Concentrically with the convex end portions of the top of the device are cylindrical openings or apertures which are carried completely through and terminate at the bottom in the same plane as the said outer cutting edge, where they are intersected in sharp cutting edges, forming the inner cutting edges 45 of the device, by outer walls which have a slight outer inclination or bevel from the bottom and terminate at said inner face of the body portion of the cutter. These inner cutting edges are concentric with the looped end 50 portions of the outer cutting edge.

Having described my invention, what I claim as new, and desire to secure by Letters Patent, is—

The design for a die or cutter for punches, 55 as herein shown and described.

In testimony whereof I affix my signature in presence of two witnesses.

OTTO SOHNI.
